UNITED STATES PATENT OFFICE.

HARRY C. NEWMAN, OF LOS ANGELES, CALIFORNIA, ASSIGNOR OF ONE-HALF TO LOREN O. CLAMPITT, OF LOS ANGELES, CALIFORNIA.

ELECTRIC VALVE-GRINDER.

1,219,142.

Specification of Letters Patent. Patented Mar. 13, 1917.

Application filed November 23, 1916. Serial No. 133,014.

To all whom it may concern:

Be it known that I, HARRY C. NEWMAN, a citizen of the United States, and a resident of Los Angeles, in the county of Los Angeles and State of California, have invented a new and Improved Electric Valve-Grinder; of which the following is a full, clear, and exact description.

This invention relates to an electrically driven tool for grinding valves.

The invention has for its objects to improve and simplify the construction and operation of devices of this character so as to be reliable, simple and efficient in use, comparatively inexpensive to manufacture, and of durable and substantial design.

A more specific object of the invention is the provision of a valve grinder so designed as to automatically impart a partial turn to the valve while the same is seated, lift the valve and impart a shorter backward turn while the valve is lifted, and indefinitely repeat its cycle until the valve is properly ground and the tool removed.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a central vertical section of the tool;

Fig. 2 is a vertical section on the line 2—2, Fig. 1;

Fig. 3 is a horizontal section on the line 3—3, Fig. 1;

Figs. 4 and 5 are detail sectional views respectively on the lines 4—4 and 5—5, Fig. 1; and

Fig. 6 is a perspective view of the spindle lifter.

Referring to the drawing, 1 designates a spindle which has at its lower end a suitable bit for engaging the valve to be ground. This spindle is rotatably and longitudinally movable in a tubular guide 3 forming part of the frame or body 4 of the tool. On the spindle or stem 1 is a collar 5 between which and the lower end of the guide 3 is a helical spring 6 which urges the spindle down-

wardly. Carried by the guide 3 is a tool rest in the form of a base ring 7 encircling the spindle, and upwardly converging spoke members 8 connect the ring with the hub member 9 which slidably fits around the 60 guide 3 to which the hub is adjustably fastened by a set-screw 10. By this means the tool rest can be adjusted upwardly or downwardly according to the depth of the valve within the engine, it being understood that 65 the base ring rests on the cylinder or frame of the engine while the tool is in operation.

Within the body 4 of the tool is a suitable motor 11 carried by a supporting plate 12.

The armature shaft 13 of the motor has a worm 14 which meshes with a worm wheel 15 on a horizontal shaft 16. This shaft has separate mutilated gears 17 and 18 which are adapted to mesh with and rotate a large bevel gear 19 which is feathered to the spindle 1. The gear 17 has a quarter of its circumference provided with gear teeth, as shown in Fig. 4, while the gear 18 has three-quarters of its circumference provided with teeth, as shown in Fig. 5, and these gears are disposed at opposite sides of the center of the large gear 19; so that the gear 18 will move the spindle 1 three-quarters of a turn forwardly, and the gear 17 will move the spindle one-quarter of a turn rearwardly. Only the forward movement of the spindle 1 is used during the grinding of the valve and its seat, and the retracing action, due to the gear 17, takes place while the valve is raised off its seat.

To permit the valve to raise, a cam-actuated lifter 20 is employed. This comprises an oscillatory member journaled on a horizontal shaft 21, and the lifter has an arm 22 which extends over the shaft 16 and is adapted to be actuated by a cam 23 on the shaft 16. The lifter has a lower arm 24 provided with a fork 25 which engages under a head or shoulder 26 on the upper end of the spindle. The cam 23 is so adjusted that the lifter is rocked to raise the spindle while the latter is being turned rearwardly by the gear 17. It is to be understood that the valve will be lifted by its own spring, the tension of which is less than the tension of the spring 6, so that when the lifter 20 is down, the spring 6 will press the valve firmly against its seat during the grinding action.

All the operator has to do is to place the 110

tool rest on the motor, engage the bit 2 with the valve, hold the tool steady by the handle 27 and turn on the current so that the motor will be driven. This produces an intermittent rotary motion of the valve in one direction with an unseating and a short backward movement between each forward step, whereby the valve and its seat will be uniformly ground.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as fall within the scope of the appended claims.

Having thus described my invention, I claim as new and desire to secure by Letters Patent:

1. A valve grinder comprising a supporting body, a rotary and axially movable valve-turning spindle, a gear connected with the spindle, mutilated gears arranged to alternately mesh with the gear to impart rotary motion in opposite directions, a lifter operatively connected with the spindle for

moving the same axially, a cam for actuating the lifter, and means for simultaneously rotating the mutilated gears and cam.

2. A valve grinder comprising a supporting body, a rotary and axially movable valve-turning spindle, a gear connected with the spindle, coaxial mutilated gears arranged to alternately mesh with the gear to impart rotary motion in opposite directions, a lifter operatively connected with the spindle for moving the same axially, a cam located between the mutilated gears for actuating the lifter, and a motor mounted on the body and operatively connected with the cam and mutilated gears for rotating the same simultaneously.

3. A valve grinding tool comprising a body, a bit-carrying spindle, a gear feathered to the spindle, mutilated gears adapted to mesh with the first-mentioned gear for moving the same forwardly a given step, and backwardly a shorter step, a shaft carrying the mutilated gear, a cam on the shaft, a lifter operatively connected with the spindle and actuated by the cam for lifting the spindle, a spring yieldingly opposing the lifting movement of the spindle, and a motor carried by the body and operatively connected with the said shaft for turning the same.

HARRY C. NEWMAN.
